HIS ATTORNEY

UNITED STATES PATENT OFFICE.

GEORGE W. PARKMAN, OF SUNNYVALE, CALIFORNIA.

CULINARY UTENSIL.

1,311,178.

Specification of Letters Patent. Patented July 29, 1919.

Application filed April 15, 1919. Serial No. 290,285.

To all whom it may concern:

Be it known that I, GEORGE W. PARKMAN, a citizen of the United States, and residing in Sunnyvale, in the county of Santa Clara 5 and State of California, have invented certain new and useful Improvements in Culinary Utensils, of which the following is a specification.

My invention relates to that class of utensils designed to receive material in the form of liquid or as a plastic mass and have the same removed therefrom in a more or less solid or coagulated form. It is the object of my invention to provide a device of the 15 character indicated which will receive a liquid without leaking and that will partially eject the coagulated or solidified substance without heating the device or using other means than I embody in the construction of the device itself. Another object is to provide a device of the character indicated that will be simple in form and construction and simple and positive in operation and economical to manufacture.

Other objects will appear in the following specification and in the drawings, in which,—

Figure 1 is a vertical cross sectional view through the device.

Fig. 2 is an enlarged plan view of the ejecting disk.

Referring more particularly to the drawing, 1 indicates a standard having a tubular shaft 2 mounted thereon, the said shaft 2 being provided with terminal fingers 3 and shoulder 4. Resting on shoulder 4 is a disk 5 having slots 6 formed therein adapted to engage fingers 3 which pass therethrough and are clenched on the top of disk 5 as shown thereby securely holding the same in place. Standard 1 has a shoulder 7 formed thereon supporting a compression spring 8 which in turn supports a receptacle 9, the latter engaging the lower surface of disk 5 as shown and preferably having a washer or gasket 10 positioned therebetween.

In the construction above set forth the cup or receptacle 9 is supported on standard 1 and held in its proper position by spring 8 maintaining it in contact with disk 5.

When, however, a jelly or other substance has been placed in receptacle 9 and has co-

agulated or solidified it may be quickly and easily removed by pressing receptacle 9 55 downwardly against the action of spring 8 to a position as indicated in dotted lines at 11, whereupon the stationary disk 5 forces the said contents of the receptacle outwardly without other manipulation. 60

It is understood that changes in form, construction, proportions and operation may be made within the scope of the appended claims. For instance the receptacle 9 may be made in an infinite variety of 65 sizes and designs, and the support therefor changed to correspond. It is pointed out that the disk 5 in the present instance also functions as a stop against the upward displacement of the receptacle. 70

I claim:

1. A culinary utensil comprising a standard comprising a foot and a shaft mounted thereon, a receptacle slidably mounted on said shaft, a resilient means supporting said receptacle on said standard, a disk secured to the upper end of said shaft and within said receptacle and coöperating with said resilient means for holding said receptacle in a normal operative position. 80

2. A culinary utensil comprising a standard comprising a foot and a shaft mounted thereon, a receptacle slidably mounted on said shaft, a resilient means supporting said receptacle on said standard, a disk secured to the upper end of said shaft and within said receptacle and coöperating with said resilient means for holding said receptacle in a normal operative position, and a gasket positioned between said receptacle and said 85 disk. 90

3. A culinary utensil comprising a standard comprising a foot and a tubular shaft provided with terminal fingers and a terminal shoulder mounted thereon, a receptacle 95 slidably mounted on said shaft, resilient means supporting said receptacle on said standard, and a disk supported on said terminal shoulder and within said receptacle and secured by clenching said fingers upon 100 the inner surface thereof, said disk coöperating with said resilient means for holding said receptacle in a normal operative position.

Executed this 7th day of April, 1919.

GEORGE W. PARKMAN.
